SPARK PLUG SHIELD

Edward N. Jacobi, Milwaukee, Wis., assignor to
 Briggs & Stratton Corporation, Milwaukee,
 Wis., a corporation of Delaware

Application January 8, 1937, Serial No. 119,543

4 Claims. (Cl. 123—169)

This invention relates to spark plug shields and has as its principal object to provide effective shielding for spark plugs against the radiation of electrical energy therefrom.

The radiation of such electrical energy, which emanates from the ungrounded portions of the plug and its lead, creates a serious disturbance and interference with radio reception, and in view of the wide use of radio receivers in automobiles and in locations where stationary internal combustion engines are in operation, it is not only desirable but essential to prevent the radiation of such energy.

Shields have been used for this purpose before, as shown in Patent No. 1,806,548 issued to Hector Rabezzana, but the shields heretofore in use have been comparatively costly and not readily applied to spark plugs in position on an engine.

It is therefore an object of this invention to simplify and improve the construction of such shields with a view toward decreasing their cost of manufacture and facilitating their application to the spark plugs.

Another object of this invention is to provide a shield of the character described which is formed in complementary sections and in which the juncture between the sections is so formed as to insure against leakage of electrical energy therethrough.

With a view toward affording ready access to the spark plug, it is a further object of this invention to provide a shield of the character described wherein the line of part between the complementary sections is on a horizontal plane normal to the axis of the plug so that when the top section is removed, the upper portion of the plug is free and unobstructed.

With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawing illustrates two complete examples of the physical embodiment of the invention constructed according to the best modes so far devised for the practical application of the principles thereof, and in which:

Figure 1 is a side view showing a shield constructed in accordance with this invention applied to a conventional spark plug and its lead;

Figure 2 is an end view thereof;

Figure 3 is a perspective view of the two complementary sections comprising the shield shown separated; and

Figure 4 is a view similar to Figure 1, but illustrating a slightly modified embodiment of the invention.

Referring now particularly to the accompanying drawing in which like numerals indicate like parts throughout the several views, the numeral 5 designates a spark plug of conventional design having a metal base 6 at its lower end by which the plug is secured in its port, and an upper porcelain end portion 7, the upper extremity of which carries a terminal 8 for the attachment of a lead wire 9. The medial portion of the plug has the conventional hexagonal nut formation 10.

The shield, designated generally by the numeral 11, is applied over the upper end portion of the plug with its lower end resting on the nut 10 and completely encloses the upper non-metallic part of the plug as well as the adjacent end portion of the conductor 9, which is the only part thereof not covered by a metallic shielding sheath 12.

The shield 11 is composed of two complementary upper and lower sections 13 and 14. These sections are identical in size and shape so that they may be formed with a single mold. The only difference between the sections is the provision of a hole 15 in the bottom wall of the lower section through which the upper end of the plug passes. The diameter of the hole 15 is such that the bottom wall of the lower section rests on top of the nut portion 10 so as to be electrically grounded thereto.

The depth at one end of the closed casing formed by the two complementary sections when in position on the plug is sufficient to dispose the top wall of the upper section a substantial distance above the top of the plug, while the opposite end of the casing through which the conductor enters is taperingly reduced, as illustrated. At this end of the casing, the meeting marginal edge portions of the two sections have recesses or notches 16 to accommodate the conductor wire.

The size of the hole formed by the recesses or notches 16 is such as to grip the shielding sheath 12 when the sections are properly engaged.

Inasmuch as variance in the diameter of the shielding sheath may preclude complete engagement of the meeting marginal edges of the sec-

tions and as leakage spaces are to be avoided, flanges are provided at the meeting marginal edges to provide an overlapping joint. To this end each section has two marginal flanges 17 and 18 at substantially diametrically opposite portions. The peripheral length of the flanges is slightly less than the corresponding unflanged portions of the marginal edges, so that when the sections are engaged, their interfitting flanges 10 produce a flange extending substantially entirely about the marginal edges of the sections. Consequently, even though the sections may separate slightly, objectionable leakage spaces are entirely avoided.

15. To hold the sections firmly connected to each other, a screw 19 is provided. The screw 19 passes through a lug 20 on the upper section, and is threaded into a tapped hole in a similar lug 21 on the lower section.

20. In this manner the casing sections are securely held together entirely independent of other fastening means.

As is noted hereinbefore, the casing is seated on the top of the nut portion 10 of the plug and 25 to firmly hold the same in place thereon a harness spring 22 anchored at its ends to the plug extends over the top of the casing.

The specific means for anchoring the ends of 30 the harness spring is, of course, susceptible to substantial modification. One convenient and practical manner of anchoring the spring is illustrated in Figures 1 and 2. As here shown, a substantially U-shaped yoke 23 embraces the metal portion of the plug directly beneath its 35 nut portion 10 with the outer ends of its arms 24 bent upwardly and extending into substantial alignment with the sides of the casing. Ears 25 bent up from the yoke engage the surfaces of the nut portion 10 to hold the yoke against turning.

40. The extremities of the harness spring are connected to the apertured arms 24, as shown and to hold the upper portion of the spring against displacement lugs 26 are formed on the casing sections as shown, and the flanges 18 are preferably cut away as at 27 to accommodate the spring and co-act with the lugs 26 in maintaining the spring in proper position.

45. As noted hereinbefore, the casing sections are securely held assembled entirely independently of the means for holding the shield in place on the plug, but if desired, the screw 19 may be eliminated and the spring 22 relied upon to hold the casing sections assembled.

50. This construction is illustrated in Figure 4. The embodiment of the invention here illustrated also utilizes a slightly different manner of anchoring the ends of the spring to the plug, a formed wire member 28 being provided in lieu of the yoke 23.

55. In all other respects, except the specific shape of the casing sections, the construction illustrated in Figure 4 is the same as that shown in Figures 1 to 3, inclusive, attention being particularly directed to the fact that the edges of the sections are also equipped with interfitting flanges to guard against leakage spaces.

From the foregoing description taken in connection with the accompanying drawing, it will be readily apparent to those skilled in the pertinent art, that this invention provides a spark plug shield which is admirably suited to the purpose for which it is intended and that it is extremely simple, both from the standpoint of manufacture and also its application to the plug.

What I claim as my invention is:

1. A shield to prevent the radiation of electrical energy from a spark plug which comprises: a casing formed of complementary sections identical in shape and construction with the exception that one of the sections has a hole through which the spark plug enters the casing; 15 interengaging flanges on the meeting edges of the sections to hold the same against relative lateral displacement; and a coil spring having its ends anchored to the spark plug and its medial portion extending over the casing in a 20 plane substantially parallel to the axis of the plug for holding the casing in place on the plug.

2. A spark plug shield comprising: two complementary sections alike as to size and shape so as to permit both to be made with one mold, 25 one of said sections having a hole in its wall opposite the open face of the section for the reception of a spark plug, and the meeting edges of the section being cut away to accommodate a lead wire running to the spark plug; flanges 30 on the meeting edge of each section to engage over unflanged portions on the other section; and means for holding the sections assembled.

3. A spark plug shield comprising: two complementary sections engaged at their marginal 35 edges to form a closed casing, one of said sections having a hole to receive a spark plug, said hole being in a wall opposite the open face of the section so that with the casing in place on a spark plug, its line of part is on a plane sub- 40 substantially normal to the spark plug axis, said sections being alike in size and shape; diagonally opposite flanges on the marginal edge of each section, said flanges having substantially the same length as the unflanged portions of the 45 marginal edges so that the flanges of one section fit over the unflanged edge portions of the other section to provide an overlapping joint extending substantially about the entire casing; and means for holding the sections assembled. 50

4. A shield for preventing the radiation of electrical energy from a spark plug which comprises: two complementary similar sections having their marginal edges abutting each other to form a housing and positively limit their movement together, one of said sections having a hole for the reception of part of a spark plug disposed in the housing; flanges extending from the marginal edges of each section adapted to overlap unflanged marginal edge portions of the 60 other section for forming a completely overlapped joint between the sections; and means for holding the sections assembled.

EDWARD N. JACOBI. 65
